UNITED STATES PATENT OFFICE.

HARRY W. FORBES AND FREDERICK LINICK, OF CHICAGO, ILLINOIS.

VAPOR-DIFFUSING DEVICE.

1,007,026.

Specification of Letters Patent.

Patented Oct. 24, 1911.

Application filed November 16, 1910. Serial No. 592,697.

To all whom it may concern:

Be it known that we, HARRY W. FORBES and FREDERICK LINICK, citizens of the United States, and residents of the city of Chicago, county of Cook, and State of Illinois, have invented certain new and useful Improvements in Vapor-Diffusing Devices, of which the following is a specification.

Our invention relates to diffusing devices and more specifically to that class thereof especially adapted for employment in the diffusion of disinfectant, aromatic, or refrigeratory fluids.

The object of our invention is the production of a device of this character especially adapted for employment in conjunction with an electric fan.

A further object of our invention is the production of a diffusing device as mentioned which will be of durable and economical construction and efficient in operation.

Other objects will appear hereinafter.

With these objects in view our invention consists in a diffusing device characterized as above mentioned and in certain details of construction and arrangements of parts all as will be hereinafter more fully described and particularly pointed out in the appended claims.

Our invention will be best understood by reference to the accompanying drawings forming a part of this specification and in which,

Figure 1 is a front elevation of a device embodying our invention, Fig. 2 is a side elevation thereof, Fig. 3 is a central section of the device detached from the electric fan or the air current producing means, and Fig. 4 is a transverse section taken on substantially line $\alpha-\alpha$ of Fig. 3.

The preferred form of our construction as illustrated in the drawings comprises a conventional electric fan which is shown as consisting of the base 1 and the casing 2 to the shaft 3 of which is secured the fan or screw 3' the latter being adapted when the armature is properly rotated to produce a forwardly directed air current. Surrounding the member 3' is the ordinary frame or skeleton guard 4.

Arranged forward of the frame 4 is a hollow cylindrical foraminated member or receptacle member 5 to opposite sides of

which are secured angularly disposed plates 6, the same being evidently adapted, when the fan is in operation, to concentrate a portion of the current produced by the fan upon the member 5. Provided at the rearward edges of the plates 6 are longitudinally extending bars 7 in which are provided longitudinally extending slots 8. Arranged upon the rearward sides of the bars 7 are straps 9 adjustably secured thereto by means of bolts 10 and nuts 11, said bolts 65 slidably engaging the slots 8 in the bars 7. The straps 9 embrace adjacent bars of the frame 4 thus serving to rigidly attach the plates 6 and hence the member 5 thereto. By reason of the adjustable connection of 70 said straps to the bars 7 it is evident that the same may be adjusted for engagement of fan guard frames of various designs.

Provided within the member 5 is a suitable absorbent filler 5' preferably of cotton or hair. The lower end of said member 5 is closed by a cap 12, the upper extremity thereof being closed by a removable cap 13, the latter being provided centrally with an upwardly projecting nipple 14. Arranged 80 axially above the member 5 is a reservoir 15 adapted to contain the fluid to be diffused. The reservoir 15 is provided with a depending nipple 16 which is connected to the nipple 14 of the cap 13 by means of a transparent or glass tube 17. The upper extremity of the reservoir 15 is provided with a filling opening, the latter being normally closed by an ordinary screw plug 18 said plug being provided with an air vent 18'. 85 The passage 19 leading from the lower end of the reservoir 15 is as will be observed quite restricted, the flow of fluid through said passage being governed by a valve 20 which is rockingly mounted in a sleeve 21 90 secured preferably by soldering in the nipple 16, said sleeve being provided with diametrically opposed perforations alining with the passage 19, said valve being provided with a passage 22 which is adapted to register with the perforations in said sleeve in order to permit of the flow of fluid thereby. When said passage 22 is not in alinement with the perforations in said sleeve, but when the same is in the position as shown 100 in Fig. 3, the flow of fluid from the passage 19 will be prevented. Formed upon the sleeve 21 in registration with the perfora-

tions at the under side thereof is a nozzle 23 the lateral extremity of which terminates within the tube 17 in such a position that the same will be visible therethrough from 5 without, as clearly shown in Fig. 3. With this arrangement it will be seen that the flow of fluid from the reservoir 15 to the receptacle 5 may be viewed from without, such provision evidently facilitating adjustment 10 of the valve 20 in the regulation of the feeding of fluid from said reservoir. Longitudinal movement of the valve 20 in the sleeve 21 is prevented in one direction by a collar 24, longitudinal movement of said valve in 15 the opposite direction being prevented by the upsetting of the opposite extremity of said valve, as clearly shown in Fig. 4. Said valve is provided with a laterally projecting elongated stem 25 upon which is carried 20 a wing or blade 26 the latter being preferably formed of aluminum in order to reduce the weight thereof. The arrangement is such that said wing will be so disposed that upon operation of the fan the current produced thereby will impinge against the same to effect the rotation of the stem 25 and hence the valve 20 in order to effect the opening of the latter. Formed integral 25 with the sleeve 21 is a bracket or arm 27 carrying at its outer extremity a U-shaped member 28 the parallel arms of which are disposed at opposite sides of one of the edges of the wing 26. Threaded in said member 28 are screws 29 and 30 which are 30 adapted to abut against the opposite sides of the wing 26 in order to limit the extent of movement thereof. With this arrangement it will be seen that by simply adjusting the screw 30 adjustment may be made 35 whereby the valve 20 will permit of full or only partial flow of fluid thereby. A torsional spring 31 having its respective extremities secured to the stem 25 and to the bracket 27 is arranged to normally hold the 40 valve 20 in closed position, said valve therefore being open, that is fluid is fed from the reservoir 15 only when the fan is in operation since in such operation the impingement of the current against the wing 26 45 rocks the same to a position against the screw 30 and hence the valve to open position.

In the operation of the device, the screw 30 being adjusted so as to permit of any 50 flow of fluid desired when the wing 26 is rocked, upon operation of the fan the fluid contained in the reservoir 15 will drain therefrom and be deposited into the receptacle 5. Here said fluid will be vaporized 55 in the filler 5' whence it will be carried by the current of air passing through the member 5 and diffused into the atmosphere.

In a device of a construction as set forth it is apparent that the diffusion of any fluid

or liquid such as a disinfectant, aromatic, etc., may be readily and effectually diffused. The device is comparatively small and hence does not to a great extent impede the current of air produced by the fan. The same is entirely automatic in its operation inasmuch as the same operates, that is liquid is fed from the reservoir to the member 5 only when the fan is in operation, such feeding being discontinued immediately upon cessation of operation of the fan. The device is of simple and economical construction hence may be manufactured at a low cost, and the same is not susceptible to readily becoming inoperative.

While we have illustrated and described the preferred form of construction for carrying our invention into effect this may be varied somewhat without departing from the spirit of the invention, we, hence do not wish to be limited to the precise details of construction as set forth but desire to avail ourselves of such variations and modifications as come within the scope of the appended claims.

Having described our invention what we claim as new and desire to secure by Letters Patent is:

1. In a device of the character described, the combination of a fluid receptacle; means for supplying fluid to said receptacle; means for directing a current of air toward said receptacle; and means for controlling the fluid supplying means, said controlling means being arranged to be operated by the air current, substantially as described. 100
2. In a device of the character described, the combination of the fluid receptacle; means for supplying fluid in said receptacle; means for directing a current of air toward said receptacle; adjustable means for controlling the fluid supplying means, said controlling means being arranged to be operated by the air current, substantially as described. 105
3. In a device of the character described, the combination of a fluid reservoir; a foraminated receptacle arranged below said reservoir and in communication therewith; means for directing a current of air toward said receptacle; and means for governing the flow of fluid from said reservoir to said receptacle, said means being adapted to permit of the flow of fluid only when said air current is being directed thereon, substantially as described. 110
4. In a device of the character described, the combination of a fluid reservoir; a foraminated receptacle arranged below said reservoir and in communication therewith; a normally closed valve controlling the flow of fluid from said reservoir to said receptacle; means for directing a current of air toward said receptacle; and means co-operat- 120

- 125

ing with said valve adapted when a current of air is directed thereon to maintain said valve in open position, substantially as described.

5. In a device of the character described, the combination of a fluid reservoir; a foraminated receptacle arranged below said reservoir and in communication therewith; a normally closed valve controlling the flow 10 of fluid from said reservoir to said receptacle; means for directing a current of air toward said receptacle; means coöperating with said valve adapted when a current of air is directed thereon to maintain said 15 valve in open position; and means coöperating with said last mentioned means for adjusting the extent to which said valve may be opened, substantially as described.

6. In a device of the character described, 20 the combination of a fluid reservoir; a foraminated receptacle arranged below said reservoir and in communication therewith; a normally closed valve controlling the flow 25 of fluid from said reservoir to said receptacle, said valve having an exteriorly projecting stem; means for directing a current of air toward said receptacle; and a wing carried in said stem against which the air current may impinge to hold said valve in 30 open position, substantially as described.

7. In a device of the character described, 35 the combination of a fluid reservoir; a foraminated receptacle arranged below said reservoir and in communication therewith; a normally closed valve controlling the flow 40 of fluid from said reservoir to said receptacle, said valve having an exteriorly projecting stem; means for directing a current of air toward said receptacle; a wing carried in said stem against which the air current may impinge to hold said valve in open 45 position; and adjustable means coöperating with said wing to limit the extent of opening movement of said valve, substantially as described.

8. In a device of the character described, 50 the combination of a fluid reservoir; a foraminated receptacle arranged below said reservoir and in communication therewith; an absorbent filler in said receptacle; a valve 55 controlling the flow of fluid from said reservoir to said receptacle; means for normally holding said valve in closed position, said valve having an exteriorly projecting stem adapted when rocked to operate said valve; a wing carried by said stem adapted to be rocked to open the valve by the impinging of an air current against the same; and means for directing an air current toward said receptacle and said wing, substantially as described.

9. In a device of the character described, 60 the combination of a fluid reservoir; a foraminated receptacle arranged below said res-

ervoir and in communication therewith; an absorbent filler in said receptacle; a valve 65 controlling the flow of fluid from said reservoir to said receptacle; resilient means for normally holding said valve in closed position, said valve having an exteriorly projecting stem adapted when rocked to operate said valve; a wing carried by said stem adapted to be rocked to open the valve by the impinging of an air current against the same; air current producing means arranged 70 rearward of and adapted to direct an air current toward said receptacle and wing; and angularly disposed concentrating plates arranged upon said receptacle, substantially as described.

10. In a device of the character described, 75 the combination of a fluid reservoir; a foraminated receptacle arranged below said reservoir and in communication therewith; an absorbent filler in said receptacle; a valve 80 controlling the flow of fluid from said reservoir to said receptacle; resilient means for normally holding said valve in closed position, said valve having an exteriorly projecting stem adapted when rocked to operate said valve; a wing carried by said stem adapted to be rocked to open the valve by the impinging of an air current against the same; adjustable means adapted to coöperate with said wing to limit the extent of 85 opening movement of said valve; air current producing means arranged rearward of and adapted to direct an air current toward said receptacle and wing; and angularly disposed concentrating plates arranged 90 upon said receptacle, substantially as described.

11. In a device of the character described, 95 the combination of a fluid reservoir; a foraminated receptacle arranged below said reservoir; a transparent tube establishing communication between said reservoir and said receptacle; a nozzle depending from said reservoir and having its lower end terminating in said transparent tube so as to be 100 visible from without; a valve mounted intermediate said reservoir and receptacle for controlling the flow of fluid from said reservoir; means for normally holding said valve in closed position, said valve having 105 an exteriorly projecting stem adapted when rocked to operate said valve; a wing carried by said stem adapted to be rocked to open the valve by the impingement of an air current against the same; and an air 110 current producer arranged rearward of and adapted to direct an air current toward said receptacle and wing, substantially as described.

12. The combination with an electric fan, 115 of a diffusing device mounted forward thereof, said device comprising a fluid reservoir; a foraminated receptacle arranged

below said reservoir; an absorbent filler in
said receptacle; a valve for governing the
flow of fluid from said reservoir to said re-
ceptacle; and means whereby when said fan
5 is in operation said valve will be open, sub-
stantially as described.

In testimony whereof we have signed our

names to this specification in the presence
of two subscribing witnesses.
